Application January 28, 1942, Serial No. 428,454

18 Claims. (Cl. 200—6)

1

The present invention relates to a control switch for electric devices, especially thermal devices such as electric heating pads, wherein a plurality of power or heat adjustments are desired.

It was known heretofore to provide control means in switches for heating pads and the like with indicating means to inform the user of the state of adjustment, both by tactual sensation as well as by visual indications. However, the latter generally consisted of marks which were invisible in the dark. It was also known to provide incandescent pilot lamps in rheostats and switches for illuminating a visible indicator or signal, but since incandescent lamps emit a relatively large amount of heat and are subject to burning out rather frequently, their use in switches of this type where the lamp is enclosed in a limited space and used for relatively long periods of time was not satisfactory.

It is an object of the present invention to provide a switch for controlling the heat or power input of a heating pad or the like with adjustment means operable not only by tactual sensation, but also having an illuminating means for an indicator, generating substantially no heat within the switch, and capable of use for very long periods without replacement.

A further disadvantage of previously known devices of the aforesaid type was that the manipulation of the adjustment member required two hands. It is, accordingly, a further object of this invention to provide adjustment means easily manipulated with one hand.

Another object of the invention is to provide a compact switch of simple construction requiring a minimum number of parts for performing several circuit control operations in a simple and effective manner, and having parts which are readily produced, for instance by stamping or molding operations and capable of assembly with maximum economy.

One feature of the invention is the provision of a switch which can be used as a combined switch and rheostat or as a multiple contact switch with only minor modifications.

Another feature of the present invention, included when the switch comprises a rheostat, is the provision of a resistance coil of especially simple and efficient construction capable of economical manufacture in mass production.

Other objects and advantages will appear hereinafter from the description of several modifications of the switch of the present invention with reference to the accompanying drawings in which:

2

Figure 1 is a plan view of a switch according to the invention.

Fig. 2 is a similar view with the cover removed.

Fig. 3 is an axial vertical cross-section of the switch of Fig. 1, taken along the line 3—3.

Fig. 4 is a detail of the manual adjustment member and indicator.

Fig. 5 is a heating pad wiring diagram including the switch of Fig. 1.

Fig. 6 is a plan view of a modification of the switch according to the present invention.

Fig. 7 is also a plan view of the switch of Fig. 6, with the cover and certain of the parts removed to show the underlying mechanism.

Fig. 8 is a vertical axial cross-section of the switch of Fig. 6 along the line 8—8.

Figs. 9a and 9b are end and side views respectively of the resistance coil of the rheostat included in the switch of Fig. 6.

Fig. 10 is a detail of the manual adjusting member and indicator included in the switch of Fig. 6.

Fig. 11 is a wiring diagram including the switch of Fig. 6.

Fig. 12 is a fragmentary view of the switch of Fig. 6 showing a modified arrangement of the resistance coil.

Fig. 13 is a perspective view of the contactor.

The switches shown in Figs. 1 and 6 include a casing 20 similar in substantially all details, which may be conveniently manufactured of molded plastic resin. The casing 20, when assembled, is of elongate shape having tapered ends and a substantially oblong, central transverse cross-section. It is separable into two parts 20a and 20b along a substantially axial plane parallel to its broader lateral surface. The two parts are held together by means of screws 21 adjacent opposite ends of the casing, and at each end, the edges of the casing parts are recessed in order to provide apertures 22 and 23, when the two halves are assembled, to receive conductors extending into the interior of the switch.

Approximately at the center of the two halves, their opposite lateral edges are recessed to form a pair of longitudinal slots 24, when the casing is assembled, through which an adjustment disk 25 carried within the casing, may extend. The casing portion 20b is also provided with a sight opening or aperture 26 for observing a visual indicator or dial 27 (or 27a), and having, if desired, a central arrow tip 28a at one side thereof.

A pair of conductors 28 entering the casing through aperture 22 at one end are adapted to connect the switch with a source of electric power. The ends of these conductors extend

through grooves 29 in the interior of the casing on opposite sides thereof, and are connected to a pair of terminal screws 30 and 31 carried by a web 32 formed in the casing half 20a. A raised portion or web 33 is formed in the central wall of the casing half 20a, comprising a semicircular portion 33a adjacent the web 32, and an oblong portion 33b extending toward the opposite end of the casing. The breadth of the web 33 is such as to allow for a pair of clearance grooves 34 and 35, between the sides thereof and the lateral casing walls, to receive connectors bypassing the said web.

A central recess 36 substantially at the center of the casing half 20a is formed in the web 33 with an annular bearing surface 37 surrounding a central spindle-receiving cavity or bearing 38 at its base. The opposite half 20b of the casing is provided with a similar bearing cavity 39 disposed directly opposite cavity 38, said cavities receiving the ends of a spindle 40 serving as the shaft for the indicator dial 27 or 27a and the adjustment disk 25. The translucent dial 27 or 27a is attached to a collar 41 on the upper end of the spindle 40 adjacent the bearing 39, and a portion of its surface extends under the sight opening 26 which is offset from the axis of the spindle.

The adjustment disk 25 may be formed for instance of molded plastic material and is of generally circular shape. It comprises a hub 42 molded on spindle 40 on the opposite side of the disk from collar 41, its lower surface forming an abutment to engage the bearing surface 37. The peripheral edges of the disk 25 extend through the lateral slots 24, so that the protruding arcuate portions of the said disk are available for its manipulation. By virtue of this arrangement, the casing 20 may be held conveniently in one hand, and the disk 25 rotated at will by a thumb or finger of the same hand. The peripheral edge of the disk 25 is knurled as indicated at 43 and is provided at intervals with buttons 44 arranged in predetermined relationship so as to provide means for adjusting the position of the disk by tactful sensation alone.

The web portion 33b of web 33 has a transverse slot 45 therein, adjacent the circular recess 36, for receiving connector or resistor means, and beyond the slot three screws 46, 47 and 48 are threaded into the web. An elevated portion of the web 33 beyond slot 45 forms an additional web 49, which carries a pair of terminal screws 50 and 51 adjacent end aperture 23. As indicated in Fig. 2, the three conductors 52a, 52b and 52c are connected to terminal screws 50, 51 and 48 respectively. These conductors are adapted to connect the switch to a device such as a heating pad to be controlled.

Terminal 30 is connected directly to terminal 51 by means of an insulated conductor 53 which lies in lateral groove 35 of the casing part 20a. Terminal 31 carries a resilient conductor strip or spring contact 54 which extends through lateral groove 34 of casing part 20a to a point opposite the spindle 40 or its bearing 38. An angular tip 55 on the spring contact 54 extends inward into the circular recess 36 through a radial groove or slot 56 in the side of the web 33, terminating just short of the hub 42. The spring contact 54 is mounted so that its resilience normally urges its tip 55 toward the top of a slot 56 in web 33.

A metal contactor 57 comprises a circular cup-shaped portion 57a having a central aperture in

its base adapted to receive the hub 42 of spindle 40, and a pair of diametrically opposite radial wings 57b, each having a pair of upturned lateral flanges 57c. The lower surface of each of the wings 57b is cylindrically convex. The upturned flanges 57c are adapted to engage a pair of correspondingly disposed apertures 58 in the adjusting disk 25 so that the disk 25 and contactor 57, when assembled as illustrated in Figs. 3 and 4, are coupled for mutual rotation.

A coiled compression spring 59 surrounds hub 42 and is supported against the face of the disk 25 at the upper end of said hub. The opposite end of the spring 59 bears upon the base of the cup-shaped portion 57a of contactor 57. Thus, when the switch is assembled, spring 59 urges the contactor 57 toward the wall of the casing half 20a, and presses wings 57b toward the upper surface of web 33, while flanges 57c thereof engage the apertures 58 in the disk 25 so that the contactor is rotatable thereby.

The tip 55 of resilient spring contact 54 is positioned beneath the lower surface of the cup-shaped portion 57a of the contactor and by virtue of its resilience, yieldably engages said contactor forming continuous electric contact therewith in all angular positions of the contactor.

The upper surface of web 33 is provided with a pair of raised portions 60 on opposite sides of the recess 36, having concave upper surfaces adapted to serve as insulating detents for yieldably holding the wings 57a of contactor 57 positioned transversely of the casing 20. One of these raised detents is split, as shown by the slot 56 through which the tip 55 of spring contact 54 extends.

In the switch of Figs. 1 to 5, terminals 46 and 48 carry a pair of conductive clips 61 and 62 respectively, which extend across the slot 45 to points adjacent the edge of the recess 36. Another clip 63, secured by screw 47, similarly extends to a point adjacent the edge of the said recess between clips 61 and 62. The upper surfaces of these clips are concave to render them capable of yieldably engaging the wings 57b of the contactor in the nature of impositive detents, and the concave surfaces of the said clips are so spaced that the detent-engaging positions of the contactor, as determined by the three clips and by the raised portions 60 on web 33, are approximately 45° apart.

A connector or bus bar 64, having its opposite ends offset from its midportion, is positioned in slot 45 beneath clips 61, 62 and 63. The offset ends thereof rest on the surface of the web 33 adjacent the ends of slot 45 and the midportion thereof extends into the said slot.

Clips 61 and 62 are permanently connected to the ends of the bus bar 64, as by soldering, while clip 63 is separated from the bar by a block 65 of insulating material and forms a detent for holding the contactor in one position as will be described.

Diametrically opposite clip 61, a metal flange 66 embedded in web 33 and protruding therefrom is formed with a concave cutout in its protruding edge, thus forming an auxiliary detent cooperating with one of the wings 57a when the other is engaged with clip 61.

Opposite clip 62, web 33 carries a terminal screw 67 to which is secured a clip 68 having a crimped contact surface 69 forming a pair of adjacent impositive detents, respectively opposite clips 62 and 63. If desired, the metal flange 66 may cooperate with the crimped surface 69

of clip 68 to form the detent opposite the central clip 63.

Terminal screw 67 is connected by a conductor or bus bar 70 to terminal screw 50, and hence to conductor 52a.

A U-shaped bracket 71 secured to the web 33 by a screw 72 carries between its arms a miniature luminous gaseous discharge tube 73, filled with some suitable gas, such as neon, at reduced pressure. The arms of bracket 71 extend between disk 25 and the translucent dial 27 so that the lamp is aligned with the sight opening 26 below said dial. Accordingly, when the lamp is illuminated, the indicia of the dial are clearly visible in the sight opening. By using a gaseous discharge tube which generates substantially no heat, the switch may be safely operated for a relatively long period of time without danger of fire or damage by overheating. Since such lamps are not subject as are incandescent lamps to burning out, they will, in general, remain operative indefinitely.

One terminal of lamp 73 is permanently connected by means of an insulated conductor 74 to spring contact 54, as by soldering, and thus to input terminal 31. The opposite lamp terminal is connected by a wire 75 to one end of a resistor 76, which adapts the lamp for use at the line voltage. The resistor 76 is carried in a pocket 77 in the wall of the casing half 20a. In the form of the invention shown in Figs. 1 to 5, the opposite end of the resistor is connected by a wire 78 to the other input terminal 30. Thus, the lamp is illuminated as long as conductors 28, attached to terminals 30 and 31, are connected to a source of energy.

Referring now to the wiring diagram of Fig. 5, the switch is shown in conjunction with a heating pad having a pair of resistances or heating coils 80 and 81, including, for example, safety devices such as fuses or thermostat switches 82. Heating coil 81 is of lower power rating while heating coil 80 is of higher power rating. One end of each heating coil is connected (at 83) to switch terminal 51 by conductor 52b. The opposite end of heating coil 80 is connected to switch terminal 50 by conductor 52a, and the opposite end of heating coil 81 is connected to switch terminal 48 by conductor 52c.

When switch contactor 57 is positioned transversely of the casing, as indicated in dotted lines in the wiring diagram of Fig. 5, the circuits through heating coils 80 and 81 are open. On turning switch contactor 57 clockwise by approximately 45° its opposite ends (i. e., the wings 57b) engage detent flange 66 and clip 61 respectively. A circuit is thereby established from terminal 31 through spring contact 54 and its tip 55, to contactor 57; thence through clip 61, bus bar 64, terminal 48, and conductor 52c to the low power heating coil 81. From the latter, the current returns via conductors 52b and 53, joined at terminal 50, to input terminal 30. Accordingly, when the contactor 57 is in this position, the low power heating coil of the heating pad is supplied with electric energy while the high power heating coil remains deenergized, and thus the pad will heat up slowly.

On turning contactor 57 clockwise through approximately 45° to the next position, that is, to the vertical position in the wiring diagram, the contactor engages insulated detent clip 63 and the opposite clip 68. A circuit is thereby established from input terminal 31 through spring contact 54 and its tip 55, to contactor 57; thence

through clip 68, terminal 67 and bus bar 70 to terminal 50; and from there through conductor 52a to the high power heating coil 80. From the latter, the circuit again traverses conductors 52b and 53 to the opposite input terminal 30. In this case, current flows in the high power heating coil, while the low power heating coil is deenergized and heat is generated at an increased rate in the pad.

Now, upon turning contactor 57, 45° further in clockwise direction, it bridges clips 62 and 68. Since the former is connected through terminal 48 and conductor 52c to the heating coil 81 and the latter is connected through bus bar 70, terminal 50 and conductor 52a, to the heating coil 80, both heating coils are simultaneously energized in parallel, the circuits from both heating coils traversing common conductors 52b and 53 to input terminal 30. This provides the maximum power setting for the heating pad.

Upon moving contactor 57 45° further in clockwise direction, it is brought again into transverse position, in which it engages insulating detents 60 on web 33, and interrupts the heating coil circuits. Further clockwise rotation of the contactor 57 effects repetition of the above-described operations. Counterclockwise rotation of contactor 57 is likewise possible, effecting the foregoing control operations in reverse order.

As shown in Fig. 4, the indicia on the dial 27, and the buttons 44 on disk 25 are so arranged with reference to disk aperture 58, that when contactor 57 is positioned transversely of the casing 20 so that the heating coils in the pad are deenergized, the word "Off" on dial 27 appears below the sight opening 26, and only the knurled periphery 43 of disk 25 without any of the buttons 44, extends through the slots 24 in the side walls of the casing 20.

When the disk 25 is rotated clockwise by approximately 45° so as to energize the low power heating coil 81, the word "Slow" on dial 27 appears in the sight opening 26, while arcuate portions of disk 25, each bearing a single button 44 at their approximate midpoint protrude through slots 24.

Further clockwise rotation of disk 25 through about 45° to energize the high power heating coil 80 brings a pair of buttons 44 to the center of each of the protruding arcuate portions of the disk 25, and the letters "Med" (standing for "medium") on dial 27, appears below the sight opening 26.

Further clockwise rotation of the disk 25 by 45° aligns the word "High" with the sight opening 26, while each protruding portion of the disk 25 now carries three buttons 44. Meanwhile, contactor 57 energizes both heating coils 80 and 81.

The next clockwise manipulation of the disk 25 again positions contactor 57 transversely of the casing corresponding to the circuit-interrupting, starting position and the word "Off" again appears in the sight opening 26, the indicia on the dial 27 being repeated on each half thereof.

Thus, as a result of provision of the illuminated dial, and of the buttons 44 on the periphery of the disk 25, the switch can be adjusted to any desired setting in the dark by tactful sensation alone, or by visual observation of the dial in the sight opening.

The switch illustrated in Figs. 6 to 11 is similar to that of Figs. 1 to 5 with the following exceptions: Screw 47, its associated clip 63, bus bar 64, and insulating block 65 are omitted, and a resistance coil 85, comprising resistance wire

wound around an insulating core 26, is inserted instead in slot 45.

Clips 61 and 62 carried by terminal screws 46 and 48 are replaced by clips 87 and 88, also extending toward recess 36, but having somewhat narrower contact surfaces than clips 61 and 62. The said clips are clamped against the opposite ends of the resistance coil 85 and form electric contact therewith. The contact surfaces of clips 87 and 88 are flat instead of concave, so that they do not act as detents in the manner of clips 61 and 62.

Detent flange 66 is omitted, and clip 68 carried by terminal screw 67 is replaced by a flat sector contact 89 which extends arcuately around the side of the recess 36 opposite slot 45, terminating adjacent the raised insulating detents 60 of web 33.

Insulated conductor 14 which joins one terminal of the pilot lamp 73 in Fig. 2 to the spring contact 52 is omitted, and the corresponding lamp terminal is connected instead by wire 90 to a clip 91, carried by terminal screw 67.

The dial 21a is mounted on the spindle 40 in the same manner as dial 21; but together with the repeated words "Off," "Low," "Medium," and "High," the dial bears a pair of graduated scales extending over arcs which correspond with the energizing adjustment ranges, and having numerical indicia which increase from "low" to "high," said scales being visible in the sight opening 26.

As a result of the foregoing differences, contactor 57, when rotated by disk 25 out of its transverse, insulated detent-engaging position in the casing 20, forms a bridge between sector contact 89 and various points on the resistance coil 85, or its terminal clips 87 and 88, and is accordingly adapted to connect these elements with terminal 31 through the spring contact 54-55.

The wiring diagram of the switch of Fig. 6 and a heating pad to be controlled thereby is shown in Fig. 11. The heating pad here comprises a main heating coil 92 with a pair of safety devices 93, such as fuses or thermostats (preferably the latter) included in its circuit. One end of the main heating coil 92 is connected to terminal 51 by conductor 52b, and thence through conductor 53 to input terminal 30 and conductor 28. The opposite end of the coil 92 is connected in series with a normally closed bimetal switch 94. The latter is connected through a pair of parallel circuits to the other input terminal 31 and its associated conductor 28.

One of these circuits traverses conductor 52c to terminal 48 and its associated clip 88 at one end of the resistance coil 85, then through the turns of the latter coil included between clip 88 and contactor 57, and finally through the latter and spring contact 54-55 to input terminal 31.

The other parallel circuit from the bimetal switch 94 to terminal 31 includes an auxiliary heating coil 95 in the heating pad, which is connected by conductor 52a to terminal 50. From the latter, it traverses bus bar 70, sector contact 89 and contactor 57, rejoining the first-described circuit at spring contact 54-55, carried by input terminal 31.

The auxiliary heating coil 95 is adapted, either alone, or in conjunction with the main heating coil 92 to control the temperature, and hence the operation, of the bimetallic switch 94. When the temperature of the bimetal 94 is sufficiently raised

by the heat generated in coil 95, possibly supplemented by that generated in coil 92, switch 94 opens, interrupting the circuit through coil 92 as well as the aforesaid parallel circuits. On cooling sufficiently, the bimetallic switch automatically recloses and reestablishes the circuits.

It will be observed that contactor 57 upon clockwise rotation from the position in which it engages insulated detent 60 initially engages clip 87 at one end of the resistor coil 85, and simultaneously, sector contact 89. Referring to the wiring diagram of Fig. 11, it will be seen that the maximum number of turns of resistance coil 85 is thereby included in parallel with auxiliary coil 95. Upon continued clockwise movement, contactor 57, while remaining in engagement with sector contact 89, moves across the coil 85 including progressively fewer and fewer turns of the resistance 85 in parallel with the auxiliary heating coil 95. Finally, it reaches clip 88 at the opposite end of said resistance coil. At this point, the resistance 85 no longer remains in the circuit, while auxiliary coil 95 is shunted, and the full line voltage is impressed across the terminals of the heating coil 92.

Since the auxiliary heating coil 95 is connected in parallel with that portion of the resistance 85 which is included between contactor 57 and clip 88, the current flowing through the main heating coil 92 is equal to the sum of the currents in auxiliary heating coil 95 and resistance 85.

In order to avoid undue generation of heat in the switch, the resistance of auxiliary coil 95 is made very much smaller than that of the main heating coil 92, so that the maximum power converted into heat in resistance 85 is never more than a very small proportion of the total power supplied to the heating pad.

When the entire resistance coil 85 is included in the circuit, that is, when contactor 57 engages clip 87, auxiliary heating coil 95 carries the maximum proportion of the current flowing through the main heating coil 92, and accordingly, heats the bimetallic switch 94 with maximum rapidity causing it to open in the shortest possible time interval after closure of the circuit. As the resistance of that portion of resistor 85 included in the circuit is decreased by clockwise rotation of contactor 57, coil 85 carries more and more of the current, and auxiliary heater 95 less and less, so that the interval between each closure of the circuit and the succeeding interruption thereof by the bimetal switch 94 becomes correspondingly longer. Finally, when coil 85 is cut out of the circuit entirely by movement of contactor 57 into engagement with clip 88 at its opposite end, coil 95 carries substantially no current, and the closed-circuit interval of switch 94 becomes maximum. In fact, with this adjustment, the switch 94 is responsive only to the heat generated by coil 92, or if the latter is not arranged to operate the bimetal switch, it remains closed, leaving the control of the circuit to the auxiliary devices 93 which in this case are thermostats.

Since the rate of cooling of the switch 94, which determines the time interval required for its reclosing the circuits is substantially the same under any given conditions of use being a function of radiation and conduction of heat by the surrounding media, the longer the circuit-closing period of switch 94 becomes as a result of the aforesaid adjustment of contact 57, the greater is the cumulative or average electrical energy converted

by heater coil 82 in a unit period of time, and the greater becomes the amount of heat generated in the pad.

Thus, upon moving the contactor 57 clockwise by corresponding rotation of disk 25, through the arc defined by its engagement with coil 85, the average power supplied to the pad may be progressively increased from a predetermined minimum to a maximum value. As in the case of the switch of Figs. 1 to 5, clockwise rotation of the disk 25 beyond the point where contactor 57 engages clip 88, returns the contactor to its transverse position in which it engages insulated detents 60, and interrupts the circuit, not only to the resistance coil 85 and its associated circuits, but also to the sector contact 89.

As indicated in Fig. 11, lamp 73 is connected, in series with its resistor 76, between terminal 30 and sector contact 89. Accordingly, in this case, the lamp is energized to illuminate dial 27a in sight opening 26 only while switch contactor 57 is turned to an energizing or circuit-closing position. However, energization of the lamp remains independent of the thermostatic switches 94 or 93 controlling the heating pad circuits. Lamp 73 could be connected to the terminals 30 and 31 as in Figs. 1 to 5 if it is desired to illuminate the dial 27a while the switch is turned "off."

The portion of the numerical scale on the dial 27a which is visible at the center of sight opening 26 gives an empirical indication of the power setting, while the accompanying words "Low," "Medium" and "High" which are similarly visible, characterize the general state of adjustment. When the lamp is extinguished the switch is "Off." The buttons 44 provide a tactful means for determining the setting of the switch in the same manner as in the case of the switch of Figs. 1 to 5.

In a modification of the switch of Figs. 6 to 11, shown in Fig. 12, clips 87 and 88 may be replaced by clips 61a and 62a, which are similar in shape to clips 61 and 62, and a clip 63a similar to clip 63, and carried by a terminal screw 47a, may be employed in conjunction with the resistance coil 85 of Figs. 6 to 11. Clips 61a and 62a, like clips 87 and 88 engage opposite ends of the resistance coil 85, while clip 63a engages the approximate midpoint of the said coil. The contact surfaces of the three clips are concave, so as to form detents cooperating with the movable contactor 57 as in the case of clips 61, 62 and 63 of Figs. 1 to 5.

Operation of this modification is similar to that of the switch of Figs. 6 to 11 except that the portion of the resistance coil 85 included in the circuit is not universally variable. Only three closed circuit adjustments are possible, namely, "low," "medium" or "high," corresponding to inclusion of all, half or none of the turns of coil 85 in the circuit by engagement of contactor 57 with clip 61a, 63a or 62a respectively. Accordingly, dial 27 of Figs. 1 to 5 is more appropriate than dial 27a when the arrangement of Fig. 12 is used.

The construction of the resistance coil 85 as shown in Figs. 9a and 9b lends itself to convenient and economical manufacture by mass production methods. Instead of employing a unitary core, the core 86 consists of two separate rectangular halves. Resistance wire 96, having an insulating coating, is wound around the juxtaposed halves of the core 86, inserting the opposite ends 97 of the said wire between the ends of the two halves adjacent the ends of the coil.

By this means, unwinding of the wire is effectively prevented and no special fastening means is required therefor.

To complete the coil, the insulation is removed from the outer surface of the wire 96 on that face of the coil 85 which is to be exposed at the top of the slot 45 so that the turns of the coil are adapted to form electrical contact with contactor 57, and with clips 87 and 88, or 61a, 62a and 63a.

Variations and modifications may be made within the scope of this invention and portions of the improvements may be used without others.

I claim:

1. In a switch for selectively connecting a pair of circuits singly or jointly to a current supply, a movable switch member having a pair of interconnected spaced contact means movable thereby into a series of spaced control positions; means for connecting said contact means to said current supply; and a pair of mutually insulated fixed contact means respectively connected to said circuits, said contact means having spaced contact surfaces so arranged with reference to the path of movement of said interconnected movable contact means that either of the latter is adapted to engage said fixed contact means and so that the two movable contact means are respectively adapted to engage said fixed contact means alternately in a pair of consecutive control positions of the switch member, to engage them simultaneously in a third consecutive position and to disengage said fixed contact means in a fourth consecutive position.
2. In a switch for selectively connecting a pair of circuits singly or jointly to a current supply, a pivoted switch member pivotally movable into a series of angularly spaced control positions and having a pair of interconnected angularly spaced contact means movable therewith and substantially equidistant from the pivot axis; means for connecting said contact means to said current supply; and a pair of mutually insulated fixed contact means having spaced contact surfaces disposed in a common plane in a circle about said pivot axis for selective engagement by said movable contact means, said fixed contact means being so arranged that the said movable contact means are respectively adapted to engage said fixed contact means alternately in a pair of consecutive control positions of said switch member and to engage said fixed contact means simultaneously in a third consecutive position.
3. In a switch for selectively connecting a pair of circuits singly or jointly to a current supply, a switch member mounted for rotation about a fixed axis; a contactor having a pair of arms extending in opposite directions from the axis of rotation of said switch member and rotatable thereby around said axis into a series of angularly spaced control positions; means for connecting said contactor to a source of electric current; fixed contact means connected to one of said circuits and adapted to be engaged by one of the arms of said contactor in a pair of consecutive control positions thereof and to be disengaged in a third control position; and fixed contact means adapted to be engaged by the opposite arm of said contactor in only one of said positions and by either arm in said third contactor position, said contactor having a fourth position in which neither of said fixed contact means is engaged, said fixed contact means lying in a common plane.
4. In a switch for selectively connecting a pair

of circuits singly or jointly to a current supply, a switch member mounted for rotation about a fixed axis; a contactor having a pair of arms extending in opposite directions from the axis of rotation of said switch member and rotatable thereby around said axis into a series of angularly spaced control positions; means for connecting said contactor to a source of electric current; fixed contact means connected to one of said circuits and adapted to be engaged by either arm of said contactor solely in a pair of consecutive positions thereof; and fixed contact means connected to the other circuit and adapted to be engaged by the opposite arm of said contactor in one of said positions and by either arm of said contactor in a third position adjacent the other of said consecutive positions, said contact means being disengaged in the latter of said consecutive positions and said contactor having a fourth position in which neither of said contact means is engaged.

5. In a switch for selectively connecting a pair of circuits singly or jointly to a current supply, a switch member mounted for rotation about a fixed axis; a contactor having a pair of arms extending in opposite directions from the axis of rotation of said switch member and rotatable thereby into a series of control positions around said axis; means for connecting said contactor to a source of electric current; fixed contact means connected to one of said circuits adapted to be engaged by one arm of said contactor solely in a pair of consecutive control positions; and fixed contact means connected to the other of said circuits and adapted to be engaged by the opposite arm of said contactor in one of said consecutive positions and in a third position adjacent the other of said positions, but not in the latter of said consecutive positions, said contactor having a fourth position adjacent the first of said consecutive positions in which neither of said contact means is engaged by the contactor.

6. A switch as defined in claim 5, wherein both of said fixed contact means are equidistant from the axis of rotation of said contactor, and the arms of the latter are of equal length so that they occupy each of said four positions twice during each complete revolution thereof.

7. A switch as defined in claim 5, wherein said fixed contact means are equidistant from the axis of rotation of said contactor, and the arms of the latter are of equal length so that they occupy each of said four positions twice during each complete revolution thereof, said switch comprising impositive yieldable detent means for retaining said contactor in each of said control positions.

8. In a multiple position switch, a casing; a switch operator rotatably mounted and disposed within the casing, said operator having a part of the periphery thereof projecting from the casing for manual engagement; a switch member coupled with said switch operator for rotation therewith and axially slidably relative thereto; a plurality of angularly spaced mutually insulated contact means in a plane normal to the axis of rotation of said switch operator; means for yieldably urging said switch member into engagement with said contact means; fixed contact means adapted to engage said switch member adjacent its axis of rotation; and means for yieldably urging the latter contact means into engagement with said switch member.

9. In a multiple position switch, a casing; a switch operator rotatably mounted and disposed

within the casing, said operator having a part of the periphery thereof projecting from the casing for manual engagement; a contact-bridging member coupled with said switch operator for rotation therewith and axially slidably relative thereto, said bridging member having oppositely disposed interconnected contact arms extending radially from the axis of rotation, each of said arms having a contact surface thereon; a plurality of angularly spaced fixed contact means in a plane normal to the axis of rotation of said switch operator and adapted to be engaged by the contact surfaces on the arms of said switch member; yieldable means engaging said switch member intermediate said contact surfaces for urging it into engagement with said contact means, fixed contact means adapted to engage said switch member intermediate its contact surfaces; and means for yieldably urging the latter contact means into engagement with said switch member.

10. In a multiple position switch, a casing; a switch operating disk rotatably mounted and disposed within the casing, the periphery of the disk projecting from the casing for manual engagement; a hub integral with said disk; a contactor having a central cup-shaped portion with a central aperture at its base adapted to receive the hub of said disk; a pair of interconnected contacting arms extending radially outward on opposite sides from said cup-shaped portion; interengaging means on said arms and said disk coupling the contactor thereto for rotation therewith, said contactor being axially slidable relative to the disk; a bearing surface having an annular series of contacts thereon concentrically arranged relative to said disk and selectively engageable with the arms of said contactor upon rotation thereof; a compression spring surrounding the hub of said disk, supported at one end by the disk and at the other end by the cup-shaped portion of said contactor, said spring urging the ends of said contactor against said bearing surface; and fixed yieldable contact means resiliently engaging the central cup-shaped portion of said switch member.

11. A switch contactor of sheet metal having a central cup-shaped portion with a central aperture at its base, a pair of arms extending radially in opposite directions from the edge of said cup-shaped portion; and a pair of lateral flanges on each of said arms bent upwardly in the same direction substantially at right angles to the plane of said arms.

12. A switch comprising a separable casing having a base portion and a cover portion; a pair of coaligned bearing means in said casing portions respectively; a switch-operating disk located within said casing and having a hub and supported for rotation in said bearings, said disk being accessible on the exterior of said casing for manual rotation; a switch member comprising a central cup-shaped portion with a central aperture therein through which the hub of the disk extends; a pair of arms extending radially in opposite directions from said cup-shaped portion; and interengaging means on said disk and said arms for coupling the disk and switch member together for rotation, said switch member remaining free to slide axially relative to said disk; a support integral with one of said casing portions having a recess concentric with said bearing means for receiving the cup-shaped portion of said switch means; contact means on said support distributed along a circle concentric with the bearing axis and adapted to be selectively

engaged by the arms of said switch member upon rotation thereof by said disk; a compression spring surrounding the hub of said disk, engaging the latter at one end and bearing against the cup-shaped portion of said switch member at the other end, said spring urging the arms of said switch member into engagement with said contacts; and a spring contactor resiliently engaging the lower surface of said cup-shaped member, said spring contact extending into said recess through a channel in said support.

13. A switch for an electric appliance comprising a hollow, elongate casing tapered at opposite ends and separable into two parts substantially along a longitudinal axial plane, the edge at a side of at least one of said parts being cut away to form a longitudinal slot in a side wall of the casing; coaligned bearing means formed in the inner surface of said respective casing parts; a switch-adjusting disk supported within the casing by said bearing means for rotation about its axis and having an arcuate peripheral portion protruding through said slot; and cutaway portions along an edge at opposite ends of at least one of said casing parts forming apertures for receiving conductors to connect the switch to a source of current and to a device to be controlled thereby.

14. A switch for controlling an electric appliance comprising a hollow, elongate casing tapering at opposite ends thereof; a pair of apertures at opposite ends of the casing for receiving electrical conductors to connect the switch to a source of current and to a device to be controlled; a longitudinal slot in the side wall of the casing; and a switch-operating disk rotatably mounted within the casing and having an arcuate peripheral portion thereof protruding through said switch for manipulation of the switch.

15. A switch for controlling an electric appliance comprising a hollow, elongate casing having a pair of apertures at opposite ends thereof to receive electrical conductors connecting the switch respectively to a source of current and to a device to be controlled; a sight aperture in a side wall of the casing, and a longitudinally disposed slot in an adjacent side wall substantially at right angles to the first-named wall; a switch-operating disk rotatably mounted within the casing having an arcuate peripheral portion protruding through said slot for manipulating the switch; and indicator means rotatable by said disk, disposed adjacent the side wall containing said sight opening and having an eccentric portion thereof visible in the sight opening.

16. In a switch, a hollow, molded casing having two portions separable along a predetermined plane; cutaway portions in the edge of at least one of said casing portions forming apertures at opposite ends of the casing for receiving conductors; coaligned bearing means in the respective portions of the casing for receiving a rotatable operating member rotatable about an axis perpendicular to the plane of separation of the casing portions; a thickened web in one of said casing portions surrounding said bearing means; terminal means carried by said web adjacent opposite ends of the casing; and a groove extending from one end of the casing to the other between

the side wall of the casing and said web portion for receiving connector means joining terminal means adjacent one end aperture to the terminal means adjacent the opposite end aperture.

5 17. In a switch, a hollow, molded casing having two portions separable along a predetermined plane; cutaway portions at the edges of at least one of said casing portions forming apertures at opposite ends of the casing for receiving conductors; coaligned bearing means in the respective portions of the casing for receiving a rotatable operating member rotatable about an axis perpendicular to the plane of separation of the casing portions; a thickened web in one of said casing portions surrounding said bearing means; terminal means carried by said web adjacent opposite ends of the casing; a groove extending from one end of the casing to the other between the side wall of the casing and said web portion for receiving connector means joining terminal means adjacent one end aperture to the terminal means adjacent the opposite end aperture; a cutaway portion in the lateral edge of at least one of said casing portions forming a longitudinally extending lateral slot when the casing is assembled, and a movable switch operator mounted in the casing and protruding through said slot.

18. A switch comprising an elongate, hollow casing; a slot extending centrally along a side 30 of the casing; bearing means within the casing located opposite the midpoint of said slot; a spindle supported by said bearing means substantially perpendicular to a plane including the slot; a switch-adjusting rotary disk carried by said 35 spindle having an arcuate portion extending through said slot for manipulating the switch; a translucent dial carried by the spindle adjacent a wall of the casing and spaced from said disk; a sight opening in said wall of the casing located 40 above an eccentric portion of the dial; a bracket supported within the casing and extending between the disk and the dial adjacent the sight opening; and a luminous gaseous discharge tube supported by said bracket and adapted to illuminate the portion of the dial visible in the sight opening.

JOSEPH YOUNHOUSE.
